CLAIM

The ornamental design for a furniture bracket as shown and described.

DESCRIPTION

FIG. 1 is a front perspective view of a furniture bracket showing my new design;

FIG. 2 is rear perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof, the left side view being a mirror image thereof;

FIG. 8 is a rear perspective view of the furniture bracket of FIGS. 1-7 shown on disclaimed environment; and,

FIG. 9 is an enlarged view of the encircled portion 9 indicated in FIG. 8.

The broken lines depicting the remainder of the furniture bracket form no part of the claimed design.
